FRANK L. ANTISELL, OF PERTH AMBOY, NEW JERSEY.

PROCESS OF AND FURNACE FOR REFINING COPPER.

1,348,470.

Specification of Letters Patent.

Patented Aug. 3, 1920.

Application filed June 6, 1913. Serial No. 772,033.

To all whom it may concern:

Be it known that I, FRANK L. ANTISELL, a citizen of the United States, and a resident of Perth Amboy, Middlesex county, 5 State of New Jersey, have invented certain new and useful Improvements in Processes of and Furnaces for Refining Copper, of which the following is a specification.

One of the objects of the invention is to 10 produce copper of a better grade and more economically than has been possible heretofore. Another object is to charge the copper into the furnace, melt it down and cast it continuously. Other objects will appear from the hereinafter description.

Before describing the invention in detail it may be well to briefly outline the prevailing process and operation of furnaces used for melting down electrolytically refined 20 cathode copper sheets. Copper in this form will run in conductivity, Matthissen standard, when refined in a solution of proper properties as high as 102%, and the copper contents of such cathodes will run in 99.97% 25 copper. When cathodes are drawn from the refining vats there is a certain amount of copper sulfate on the surface thereof. It has been found impracticable to entirely eliminate the copper sulfate, and it has 30 therefore been customary to give the sheets only a superficial washing and then charge them into a furnace, generally of the reverberatory type, for the purpose of melting the cathodes down into such commercial 35 shape as the market demands. The cathodes besides being coated with copper sulfate are also coated to a greater or less extent with metallic arsenic which some copper in the cathode has thrown out of the solution. 40 While the arsenic is necessarily small in amount, it has the characteristic of lowering the electrical conductivity if present as the metallic element in alloy with the copper, and when the copper is melted down in the 45 furnace in the usual practice, a greater or less amount of impurities, such as arsenic and antimony, forming eutectoids which are detrimental to the electrical properties of copper, so it has been customary after 50 the charge has been melted, to flap it down, or in other words, oxidize the copper either with compressed air, blowing with a small pipe into the bath, or causing a large volume of air to blow over the bath and agitate 55 the surface of the molten copper with suitable appliances.

During this operation some slag is produced and the copper sulfid which has been formed is disassociated by the well known formula of copper oxid acting on copper sulfid, forming metallic copper and SO_2 gas, which, by proper manipulation of the bath, will be mechanically driven off.

It has been generally customary to carry on this oxidization to a point where a sample of the copper will show large crystals due to sub-oxid of copper. Some refineries term this matrix a block, and they say a large block or a small block, thus in a rough way, indicating a greater or less amount of sub-oxid in solution in the copper. The greater the amount of arsenic in the copper up to a certain limit (.100%) the more sub-oxid is necessary to introduce in the bath, for the reason of effecting oxidization 75 of the arsenic, and it is necessary at times to introduce as much as 20% of the copper as sub-oxid. After the molten copper has been subject to this oxidizing treatment and the slag skimmed off, which will contain 80 iron, zinc, etc., (if present in the charge) the copper is subjected to another step in the art of refining known as "poling" or "deoxidizing" the copper. This is generally effected by covering the surface of the molten copper with charcoal, coke, or coal, and forcing a stick of wood under the surface of the bath. Some of the oxids of copper in this way are reduced to metallic copper 85 and the reduction is carried on until a point 90 is reached when the sub-oxid is reduced to a fraction of 1%. It is necessary that this deoxidization be not carried too far, otherwise, the arsenic and antimony which is present will be reduced to a metallic state 95 alloying with the copper and thus reducing the electrical conductivity. At the same time, it is desirable to reduce the oxid of copper to the lowest percentage possible and still not reduce the other oxids present. 100 In this manner the highest electrical conductivity is obtained.

I have overcome the objections to the prior process of refining and have simplified and cheapened the same by the process 105 hereinafter described which may be carried out by different furnaces, but in the accompanying drawing I have shown a furnace especially adapted for carrying out said improved process.

This application is a continuation in part 110 of my prior applications Serial No. 608,935,

filed Feb. 6, 1911, and Serial No. 728,984.
filed November 1, 1912.

Referring to the drawing:

Figure 1 is a vertical section of a furnace 5 for carrying out the improved process taken on line 1 of Fig. 2.

Fig. 2 is a horizontal sectional view on the staggered line 2—2 of Fig. 1.

Fig. 3 is a section through the shaft or 10 chimney of the furnace showing the arrangements of the cathodes as they are charged into the furnace through the stack.

Fig. 4 is a horizontal view showing a slight modification of the construction of 15 the stack.

Fig. 5 is a top plan view of a modified construction of stack.

Fig. 6 is a sectional view on line 6 of 20 Fig. 5.

Fig. 7 is a sectional view on line 7 of Fig. 5.

Referring first to Figs. 1 and 2, the part marked A represents the furnace proper. B is the stack divided by the partition B' to 25 form flues B² and B³. The partition B' extends nearly to the bottom of the stack and the two flues are connected to the furnace hearth C by the passageway D. The furnace A is divided by the partition E into 30 a casting compartment C' and a melting compartment C². The object of the partition E is to baffle the currents of copper in the hearth as they pass from one compartment to the other.

F is an air cooled bridge wall and G is a 35 fire box provided with grate bars H to support a bed of coal which is used in the furnace for melting down copper. J is an air pipe leading from a suitable source of supply 40 and is connected to the stack B and is provided with a branch J', which leads to the fire box G. Each branch is controlled by suitable valves or dampers j and j'. The roof of the furnace is provided with a 45 port or opening a, through which sticks of wood may be inserted for the purpose of poling or through which pipes for supplying crude oil may be introduced.

In Fig. 4 I have shown a slightly modified construction in which the stack is provided with only one flue and in this case, as in the prior described constructions, the cathodes are charged crosswise in the stack as shown. Fig. 3 is a perspective view to 55 more clearly show the arrangement of the cathodes in the stack.

The operation of this improved furnace is as follows: Coal is placed on the grate bars H and the fire is started and the furnace is heated up to melting point of copper. When this temperature is reached the cathode copper is charged into the stack as follows: A cathode plate is charged diagonally across the flue and is lowered until 60 the bottom edge rests upon that part of

the furnace marked a'. Another cathode 2 is then charged diagonally in the flue but crossing the first cathode, and this arrangement is carried out until the stack is full of cathode plates. By this arrangement of 70 cathodes the products of combustion have free egress and the cathodes are heated by the outgoing products of combustion. As the lower cathode sheet melts or liquefies, the molten metal flows from compartment 75 c² and under the partition or baffle E into the compartment c'. The charging and melting down is carried on continuously until the metal in the hearth C reaches a predetermined point. During the melting 80 down the charge has been sufficiently oxidized through the agency of free oxygen introduced into the stack through the pipe J and into the combustion chamber of the furnace through the pipe J'.

After the copper has remained long enough in the compartment c² to permit the necessary reactions to take place, for instance, the copper oxid acting on the copper sulfid forming metallic copper and 85 SO₂ gas, it passes into compartment c'. If any sulfid should be carried into the bath, which likelihood is reduced to a minimum owing to the thorough roasting of the cathodes during their descent in the stack 90 and into the zone of the furnace, the copper in compartment c² is thus automatically maintained at such a point of saturation of sub-oxid as will insure the presence of 95 the impurities as oxid.

In this furnace it is not necessary to introduce as much sub-oxid in the copper when melted down as is the case in the ordinary reverberatory furnace heretofore used where the copper has been charged on 1 the hearth. The molten copper from compartment c² flows under the partition or baffle E into compartment c' where it is further heated by the flame passing over the air cooled bridge wall F where it is de-oxidized to the proper point with hydrocarbon gases derived from the combustion of green poles inserted through the opening a, or from petroleum supplied through pipes inserted through said opening. Properly the deoxidized copper is then drawn out of compartment c' through a suitable tap hole c to a casting apparatus, where it is cast into suitable form for commercial use.

I wish it to be distinctly understood that in my present invention I do not propose to use crude petroleum oil or its by-products as a source of heat for melting down the copper, although I do use this form of hydrocarbon for the purpose of de-oxidizing the copper after it reaches the compartment c'.

In Figs. 5, 6 and 7 I have shown a slightly modified construction of the top end of the

stack or flue marked B'. In this construction the outlet end of the stack is "tumbled in" or contracted as shown at b, with criss-cross passages or channel-ways b' for the insertion of the cathode plates 1, 2, 3, etc. In this construction the products of combustion do not pass out of the stack as freely as in the open construction and, therefore, the heat is retained in the stack somewhat longer.

By this furnace and the described process I am able to produce better copper for the reason that such arsenic as is on the surface of the cathodes supplied through the stack 15 is gradually heated by the outgoing products of combustion until it is partially volatilized and roasted to an oxid resulting in an elimination of about 50% of the total arsenic contents of the cathodes. The antimony carried 20 by the cathodes is also partially volatilized, resulting in an elimination of about 20% of the antimony carried by the cathodes. It is to be understood that these figures apply to high grade cathode sheets, where the 25 arsenic and antimony originally are present in both cases to about .0015%. As the operation is carried on continuously the economy is apparent when it is considered that the cold cathode plates are charged 30 into the comparatively cold portion of the furnace and preheated by the products of combustion that have previously heated copper lower down in the stack, and as the ascending gases or outgoing products of combustion meet the incoming charge or cathode plates by reason of the lower sheet being in 35 the melting zone of the furnace, and as the lower sheet dissolves or melts the upper sheet coming gradually into the heated zone 40 on the counter current principle, the heat that would otherwise be lost is utilized for heating the copper.

In an ordinary reverberatory furnace the efficiency of the furnace is about 10%. With 45 this furnace by actual practice, an efficiency of 45% has been effected and as the hearth is small in proportion to the amount of copper melted in a given period of time, the radiation losses are reduced. This fact 50 partially accounts for the high efficiency hereinabove stated.

Then again, by maintaining a large proportion of impurities as oxid during the melting, it is not necessary to bring the copper down to as "low" a point in sub-oxid as if the arsenic had been allowed in its metallic state and a large percentage of the cost of deoxidizing the copper is therefore obviated.

60 The continuous operation of the furnace is evident from the fact that the furnace can be charged continuously at the top of the stack and the bottommost cathode be continuously melted and the molten copper in

the hearth can be continuously removed from 65 the compartment c'.

In the drawing only one cathode sheet to each layer is shown, but this is only suggestive, as the cathodes may be successfully melted down with as many as a dozen plates 70 placed side by side, or in a single layer. It is only necessary that the plates should be placed so that there will be free exit of the products of combustion and a free circulation of said products against the surfaces of the cathodes.

It is evident that the source of heat is from the fire box G, and the flame passes over the bridge wall F and it raises the temperature of the metal in the hearth to the 80 proper point as high above the melting temperature as desirable for casting, and the flame then ascending the stack preheats the incoming charge of copper. The rate at which the melting is carried on and the 85 amount of oxid formed on the surface of the cathode depends to a great extent upon the amount of submergence that the bottom of the copper has in the bath and molten metal. The deeper the submergence the 90 greater the rate of melting of the copper and the less the submergence the greater the oxidization of the copper. In other words, if the copper melts at such a high rate that the oxidization has not been completed before the lowermost cathode enters the melting zone, the submergence is decreased. This means regulation is necessary for the reason that the cathodes charged are of varying weights. The heavier the cathode the slower 95 it will melt, and to a very large extent the submergence is regulated by raising or lowering the metal line in the furnace.

It is to be noted that the copper plates are so arranged that they continuously and successively gravitate in series to the melting chamber, and the products of combustion continuously pass upward in a direction opposite to the movement of the plates so that the combustion products successively pass 110 by and operate serially upon the said plates. I define this counter movement of the plates and the products of combustion as a counter current operation.

In carrying out my process, the steps of 115 pre-heating and of roasting are each effected by means of a heat which is not sufficient to melt the copper, and therefore the step of pre-heating and the step of roasting in my process are clearly distinguishable from the 120 initial action of the melting heat upon the copper. The pre-heating and the roasting are never accomplished by the action of the melting heat, but are always accomplished by a heat which is always less than 125 the melting heat and insufficient to accomplish the melting of the copper. It is in this sense that I have used the words "pre-heat-

4
ing" and "roasting" in the specification and claims.

Having now described my invention, what I claim as new and desire to secure by Letters Patent is:

1. The process of refining copper which consists in continuously, progressively and serially pre-heating, roasting and melting copper forms separately and individually.
10. 2. The process of refining copper which consists in continuously, progressively and serially roasting copper forms and then subjecting the said copper forms separately and individually to a melting temperature.
15. 3. The process of refining copper which consists in gradually feeding copper forms to the melting zone where they are melted separately and individually and progressively and serially pre-heating and roasting said copper while being so fed.
20. 4. The process of refining copper which consists in continuously, progressively and serially pre-heating and roasting copper forms and then subjecting the copper forms to a melting temperature so that they are melted separately and individually.
25. 5. The process of refining copper which consists in continuously feeding copper forms to a melting zone, melting the copper forms in said zone separately and individually, preheating and roasting the copper forms serially by a current of products of combustion passing counterwise to the direction of the feed.
30. 35. 6. The process of refining copper which consists in progressively and serially melting copper forms separately and individually, roasting the copper to be melted and pre-heating the copper to be roasted.
40. 45. 7. The process of refining copper which consists in continuously feeding copper forms in series through a pre-heating zone then through a roasting zone and then to a melting zone so that said forms are melted separately and individually and then super-heating the fused copper.
50. 55. 8. The process of refining copper which consists in continuously feeding copper blanks in series through a pre-heating zone, then through a roasting zone, then to a melting zone, melting the copper forms in said zone separately and individually and then super-heating the melted copper and then feeding the melted copper to a de-oxidizing zone.
60. 65. 9. The process of refining copper which consists in continuously feeding copper blanks in series through a pre-heating zone, through a roasting zone, to a melting zone, where said forms are melted separately and individually and then super-heating the melted copper and then feeding said melted copper to a de-oxidizing zone and then continuously removing the copper from the de-oxidizing zone.
10. The process of refining copper which consists in progressively preheating and roasting copper forms in series, then progressively subjecting said forms to a melting temperature so that said forms are melted separately and individually, holding the copper at that temperature until the necessary reaction takes place, then raising the temperature to a casting heat and deoxidizing at that heat.

the copper, subjecting the lowest plate to a melting temperature, and holding the copper at that temperature until the necessary reaction takes place.

- 5 17. The process of refining cathode copper which consists in melting the cathodes and passing the products of combustion by which the melting is effected along the surfaces of a series of cathodes arranged in vertical succession in advance of the melting zone, each cathode resting upon and supported by the one next below, whereby the cathodes before being subjected to a melting temperature are caused to melt separately 15 and individually to move gravitally and in series through zones of heat of successively increasing temperature derived from the products of combustion.
18. The process of refining cathode copper which consists in melting the cathodes and passing the products of combustion by which the melting is effected along the surfaces of a series of cathodes loosely arranged in vertical succession in advance of 20 the melting zone, each cathode being in contact with and supported by the one next below, whereby the cathodes before being subjected to a melting temperature are caused to melt separately and individually 25 to move gravitally and in series through zones of heat of successively increasing temperature derived from the products of combustion.
19. The process of refining cathode copper which consists in melting the cathodes and passing the products of combustion by which the melting is effected along the surfaces of a series of cathodes arranged in criss-cross fashion in vertical succession in 30 advance of the melting chamber, whereby the cathodes before being subjected to a melting temperature are caused to move gravitally through zones of heat of successively increasing temperature derived 35 from the products of combustion.
20. The process of treating copper, which consists in continuously melting copper forms separately and individually by means of the highly heated products of combustion 40 of a hydrocarbon burner regulated to produce an oxidizing atmosphere, thereby producing an amount of copper oxid in said copper, and liberating the oxygen from said oxid by commingling with the copper a reducing agent, and purifying said copper. 45

21. A furnace for treating copper comprising a hearth having melting and refining chambers communicating with each other, and a stack having communication with one end of said chamber and through which all the products of combustion pass and the material to be refined is introduced into the hearth. 60

22. A furnace for treating copper comprising a melting chamber, a stack having communication with one end of said chamber and through which all the products of combustion pass and the material to be treated is introduced thereto, grate bars arranged at the other end of the chamber, 70 and a bridge wall between the grate bars and the chamber.

23. A furnace for treating copper comprising a melting chamber having means for supplying a melting flame thereto, a stack 75 having communication with said chamber, said stack having its outlet end contracted and provided with an opening through which the material to be treated may be introduced into the stack, the contracted end 80 of the stack being otherwise closed to partially confine the products of combustion.

24. A furnace for treating copper comprising a melting chamber having means for supplying a melting flame thereto, a 85 stack having communication with said chamber, said stack having its outlet end contracted and provided with openings arranged in criss-cross fashion for the introduction of the material to be treated, and 90 to partially confine the products of combustion.

25. A furnace for treating copper comprising a melting chamber, a combustion chamber having communication with one 95 end thereof, a stack having communication with the other end of the melting chamber, said stack serving to feed the material to be treated to the melting chamber, and valved means for supplying air, having one 100 branch to the stack and another branch to the combustion chamber.

In witness whereof I have hereunto set my hand at Perth Amboy, county of Middlesex and State of New Jersey, this fourth 105 day of June, 1913.

FRANK L. ANTISELL.
